UNITED STATES PATENT OFFICE.

CLARENCE GREGG, OF PITT BRIDGE, TEXAS.

MACHINE-GUN.

1,277,307.

Specification of Letters Patent. Patented Aug. 21, 1918.

Application filed January 4, 1918. Serial No. 210,289.

To all whom it may concern:

Be it known that I, CLARENCE GREGG, a citizen of the United States, residing at Pitt Bridge, in the county of Burleson and State of Texas, have invented certain new and useful Improvements in Machine-Guns, of which the following is a specification.

This invention relates to improvements in machine guns and it is the principal object of 10 the invention to provide a machine gun so constructed as to permit the simultaneous discharge of a plurality of cartridges therein, and the projection of the bullets therefrom in a manner such as will cause the same to 15 effectually sweep the path of travel thereof. Another and equally important object of the invention is to provide novel means for effecting the simultaneous discharge of the cartridges arranged in the gun, the same being 20 automatically operated.

It is also an object of the invention to provide a novel form of magazine for the gun, whereby the cartridges will be properly fed into the breech portions of the various barrels of the gun, the magazine being raised in step by step fashion and the cartridges carried to positions in alignment with the bores of the gun barrels.

Other independent objects are to provide 25 features of construction of portions of the gun, which tend toward the attainment of the above aims irrespective of the relation in which they are used.

Other objects will be in part obvious and 30 in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of my invention:

Figure 1 is a front elevation of the improved gun having parts thereof shown in section,

Fig. 2 is a top plan having parts shown in 50 section,

Fig. 3 is a vertical longitudinal section through the gun,

Fig. 4 is a fragmentary detail in perspective of the means for raising the magazine,

Fig. 5 is a detail in perspective of the gun base or support,

Fig. 6 is a diagrammatic view showing the manner in which the various firing pins of the gun are actuated, and

Fig. 7 is a fragmental detail of the gun shield.

Similar reference characters refer to similar parts throughout the several views of the drawings.

Having more especial reference to the drawings, 1 represents the base of the gun, the same having oppositely disposed vertical standards 2 arranged adjacent one end thereof, the upper ends of said standards being apertured, for a purpose which will 70 be subsequently apparent. A gun barrel support 3 is pivotally supported between the upper ends of the standards 2, suitable bearing pintles being engaged in the apertured upper ends of said standards. In this connection, it is to be noted that the outer marginal portion of the support 3 is convex, while a plurality of radially disposed openings are formed in the same and receive a plurality of gun barrels 4 therein.

The frame comprising oppositely disposed side pieces 5 and a bottom 6 is provided, the side pieces having metal strips 7 arranged adjacent the outer faces thereof, certain of the ends of said strips being bent at substantially right angles as at 8 to engage the adjacent marginal portions of the sides. Ways 10 are formed in the adjacent faces of the side pieces 5 and extend longitudinally of the same, serving as means for slidably retaining a magazine 11, which as will be noted includes a substantially rectangular frame having a plurality of cartridge receiving and supporting racks 12 extending transversely therethrough and having their 95 opposite ends securely engaged with the adjacent sides of said frame. Ratchet members 13 are secured to the adjacent or inner faces of the side pieces 5 by a suitable means and are adapted to be engaged by a spring 106 pressed pawl 14 suitably mounted upon the lower end of the magazine 11.

As means for raising the magazine 11 in order that the various cartridge retaining racks 12 may be aligned with the breech portions of the various barrels 4, a ratchet bar 15 having an off-set upper end 16 is passed through an opening 17 formed in the bottom piece 6 of the frame into pivotal engagement with a lever 18 as at 19, the said 110 lever, as will be noted, being pivotally engaged with the bracket arm secured to the

forward end of the bottom piece 6 and designated by the numeral 20. A guide rod 21 is passed through an opening formed in the off-set portion 16 of the bar 15 into engagement with the adjacent portion of the frame and has a contractile spring 22 arranged thereabout. In this way, it will be readily understood that the upper end of the ratchet bar will be normally drawn in a direction toward the magazine 11 and hence, the ratchet teeth formed thereon will be constantly engaged with an adjacent portion of said magazine 11. Rotatably mounted on the bottom piece 6 is a crank shaft 23 having one end thereof squared and engaged with an arm 24, which arm in turn is pivotally engaged with a second arm 25 having its remaining end pivotally connected to the outer end of the lever 18 as at 26. Thus, by 20 rocking the crank shaft 23 vertical movement will be imparted to the ratchet bar 15 and as a consequence, the magazine 11 will be raised in the frame of the machine gun in a step by step fashion; the pawls 14 engaging the various ratchet pieces 13 and serving as means for supporting the same in its adjusted position.

Pivottally mounted upon the under side of the bottom piece 6 of the machine gun frame 30 is an internally screw threaded collar 27 which receives one end of a screw threaded shaft 28 therethrough, the outer end of said shaft passing through the second pivotally supported internally screw threaded collar 35 29 and having a crank handle 30 pivotally mounted thereon. Obviously, by rotating the screw threaded shaft 28 the machine gun frame, which is pivotally supported upon the upper ends of the vertical standards 2 40 will be swung to a position such as will permit the varying of the range of the gun. Inasmuch, as the barrel support 3 is connected to the frame, it of course will be understood that the various barrels 4 will be 45 moved in a direction corresponding to the movement of the magazine 11 and as a consequence, the feeding of cartridges into the breech portions of said barrels will be at all times permitted, irrespective of the adjustment of the same.

With a view toward providing means for effecting a discharge of those cartridges arranged at positions in alinement with the breech portions of the gun barrels 4, secured 55 to the upper portions of the side pieces of the gun frame a transversely disposed bar 31 having a plurality of openings formed therein for slidably receiving a plurality of firing pins 32. A second bar 33 is slidably 60 mounted rearwardly of the bar 32 and has its opposite end arranged directly over the poles of electro-magnets 34, which magnets, as will be noted, are included in an electrical circuit formed by the conductors α and α' ; 65 said conductors including a suitable source

of energy b and having a circuit closing element c arranged therein. Thus, upon the closing of the electrical circuit, the bar 33 will be drawn abruptly into engagement with the rear ends of the firing pins 32, 70 thereby causing the same to sharply strike the fulminates of the cartridges arranged in the magazine at points in alinement with the rear ends or breech portions of the various gun barrels 4; causing the same to be 75 exploded and the bullets to be projected through the gun barrels forwardly thereof. When the cartridges in one rack of the magazine have been exploded, it is of course only necessary to operate the crank 23 to 80 cause the lower rack of cartridges to be raised to a position in alinement with the breech portions of the gun barrels, whereupon they may be discharged by closing the electrical circuit and causing the operation 85 of the various firing pins 32. Such operation may be carried on until the supply of cartridges in the magazine has been exhausted. The magazine may be reloaded or if desired, may be removed from the gun 90 frame and a fresh magazine substituted therefor, thereby rendering the gun ready for further operation.

A shield 35, substantially V-shaped in cross section and having an elongated slot 36 formed in the upper portion thereof is provided and as will be understood, is formed integral with the strips 7. The shield is secured in position forwardly of a machine gun, the rear portions thereof being secured to the sides of the gun frame by suitable fastening devices passing therethrough. To allow the arranging of the rear portions of said shield over the electro-magnets 34, portions of the same are off-set 100 as at 37 and as will be appreciated, receive the magnets therein. The slot 36 is alined with the outer end of the various gun barrels 4, thereby permitting the projectiles discharged from the same to pass there- 110 through.

Manifestly, the construction shown is capable of considerable modification and such modification as is within the scope of my claims, I consider within the spirit of my invention.

I claim:

1. In a machine gun, a base having standards arranged thereon, a frame pivoted between said standards, a plurality of radially disposed barrels arranged on said frame, a vertically movable magazine arranged on the frame adapted to aline cartridges with the breech portions of said barrels, a lever connected to said frame, an upright ratchet bar pivoted at its lower end to the lever and passing upwardly through the frame adapted for engagement with the magazine, means for rocking said lever, ratchet bars arranged adjacent the inner faces of the 120

125

130

frame, and pawls carried by the magazine engageable with the second mentioned ratchet bars.

2. In a machine gun, a base having spaced standards thereon, ratchet bars arranged adjacent the inner faces of standards of the frame, a frame pivoted between the standards, a plurality of barrels carried by the frame, a vertically movable magazine arranged on the frame adapted to align cartridges with the breech portions of the gun barrels, a lever connected to the frame, means for rocking said lever, a ratchet bar pivoted at its lower end to said lever and extending

upwardly through the frame adapted for engagement with said magazine, means for yieldably connecting the upper end of said second mentioned ratchet bar to the adjacent portion of said frame, pawls carried by the magazine engageable with said first mentioned ratchet bars, and means for effecting the simultaneous discharge of cartridges aligned with the breech portions of the barrels.

In testimony whereof, I affix my signature hereto.

CLARENCE GREGG.
